UNITED STATES PATENT OFFICE

93,186

DESIGN FOR A REFRIGERATOR CABINET

Ture G. Shelin, Elmwood Park, and Frank J. Fuchs, Chicago, Ill., assignors to Grigsby-Grunow Company, Chicago, Ill., a corporation of Illinois; Frank M. McKey, receiver in bankruptcy

Application June 12, 1933, Serial No. 48,384

Term of patent 7 years

To all whom it may concern:

Be it known, that TURE G. SHELIN and FRANK J. FUCHS, citizens of the United States of America, residing at Elmwood Park and Chicago, respectively, in the county of Cook and State of Illinois, have invented a new, original, and ornamental Design for Refrigerator Cabinets, of which the following is a specification, reference being had to the accompanying drawing, forming part thereof.

The figure is a perspective view of the refrigerator cabinet showing our new design.

We claim:

The ornamental design for a refrigerator cabinet as shown.

In testimony whereof they affix their signatures.

TURE G. SHELIN.
FRANK J. FUCHS.
